United States Patent Office

Des. 197,476
Patented Feb. 11, 1964

197,476

COVERED SERVING DISH

Ronald G. De Puy, 18 Lower Drive, and Jerry E. Wright,
72 Catherine St., both of Corning, N.Y.

Filed Sept. 4, 1963, Ser. No. 76,484

Term of patent 14 years

(Cl. D44—15)

Fig. 1

Fig. 2

Fig. 3

Fig. 4

Fig. 5

We claim:

The ornamental design for a covered serving dish, as shown.
